UNITED STATES PATENT OFFICE

119,263

DESIGN FOR A LEAD PROPELLING PENCIL

Carl C. Harris, Orange, Mass.

Application November 29, 1939, Serial No. 88,549

Term of patent 14 years

To all whom it may concern:

Be it known that I, Carl C. Harris, a citizen of the United States, residing at Orange, Massachusetts, have invented a new, original, and ornamental Design for Lead Propelling Pencils, of which the following is a specification, reference being had to the accompanying drawing, forming part thereof.

In the drawing:

Fig. 1 is a perspective view of a lead propelling pencil showing my new design;

Fig. 2 is a plan view showing the cap detached from the pencil body;

Fig. 3 is an edge elevation also showing the cap detached from the pencil body.

I claim:

The ornamental design for a lead propelling pencil, as shown.

CARL C. HARRIS.
